DESIGN FOR AN OVERSHOE

Hubert C. Watson, New York, N. Y.

Application August 12, 1938, Serial No. 79,296

Term of patent 3½ years

To all whom it may concern:

Be it known that I, Hubert C. Watson, a citizen of the United States, residing at New York, in the county of New York and State of New York, have invented a new, original, and ornamental Design for an Overshoe, of which the following is a specification, reference being had to the accompanying drawing, forming a part thereof.

I claim:

The ornamental design for an overshoe, as shown.

HUBERT C. WATSON.
